UNITED STATES PATENT OFFICE.

CHARLES B. McELROY AND THOMAS W. MINSHULL, OF CLEVELAND, OHIO.

DESIGN FOR A BADGE.

SPECIFICATION forming part of Design No. 20,580, dated March 10, 1891.

Application filed January 19, 1891. Serial No. 378,362. Term of patent 7 years.

To all whom it may concern:

Be it known that we, CHARLES B. McELROY and THOMAS W. MINSHULL, citizens of the United States, and residents of Cleveland, in the county of Cuyahoga and State of Ohio, have invented and produced a new and original Design for Society Badges and Charms, of which the following is a specification, reference being had to the accompanying photograph or illustration, forming part thereof.

The illustration represents a plan view of an approximately full-sized badge embodying our design.

The leading features of our design consist in a figure representing a sash or baldric circularly or elliptically arranged, and in a figure representing a cross located within the outer line or border of said sash or baldric, the cross having centrally mounted thereon figures representing, respectively, a crown, a sword, and a wand, and the cross is topped or headed by a figure representing a helmet.

A represents the figure of a sash or baldric

that, as shown, is circularly or elliptically arranged. Located within the outer line or border of this sash or baldric is a figure b, representing a cross. The latter is topped or headed by a figure c, representing a helmet, and has centrally mounted thereon figures d e f, representing, respectively, a crown, a sword, and a wand, and below the figure representing the cross the end sections of sash or baldric A are represented as overlapping each other, as shown at a.

What we claim is—

The design for a badge herein shown and described.

In testimony whereof we sign this specification, in the presence of two witnesses, this 3d day of January, 1891.

CHARLES B. McELROY.
THOMAS W. MINSHULL.
